UNITED STATES PATENT OFFICE.

EDWARD J. OVINGTON, OF BROOKLYN, NEW YORK.

DESIGN FOR A PITCHER.

SPECIFICATION forming part of Design No. 12,597, dated December 13, 1881.

Application filed November 10, 1881. Term of patent 3½ years.

To all whom it may concern:

Be it known that I, EDWARD J. OVINGTON, of Brooklyn, Kings county, New York, have invented a new and original Design for a Pitcher, of which the following specification is a full, clear, and exact description, reference being had to the accompanying drawing, forming part of this specification.

The drawing represents a side view of a pitcher having my new design.

This invention relates to a new ornamentation for a pitcher or other china household article, such as a tea-pot, sugar-box, fruit-bowl, cup and saucer, spittoon, or covered butter-dish.

It consists of the representation of an encircling band or ribbon, A, with tie a, in connection with floral ornamentation B. This floral ornamentation is composed of flowers b and leaves c.

The design is applied in suitable colors.

I claim as my invention—

1. The design for a pitcher, consisting of encircling ribbon A and floral ornamentation B, substantially as shown.

2. The design for a pitcher, consisting of ribbon A, with its tie a, and of floral ornamentation B, with its flowers b and leaves c, substantially as shown.

EDWARD J. OVINGTON.
